UNITED STATES PATENT OFFICE.

HENRY M. CURRY, JR., OF PITTSBURGH, AND LEO FINEGAN, OF ZELIENOPLE, PENNSYLVANIA, ASSIGNEES TO THE PREMIER STAYBOLT COMPANY, OF PITTSBURGH, PENNSYLVANIA, A CORPORATION OF PENNSYLVANIA.

MANUFACTURE OF STAY BOLTS.

Application filed November 15, 1926. Serial No. 148,357.

This invention relates to the manufacture of staybolts, and more particularly to hollow staybolts having an enlarged solid head formed integral with the hollow body of the bolt.

The manufacture of bolts of this class has heretofore been a matter of considerable difficulty. The formation of the central bore in such bolts after they are formed by 10 boring or drilling is difficult and expensive, due to the small diameter and length of the bore which requires a small diameter drill of considerable length, necessitating slow drilling in order to prevent excessive breakage of the drills.

The present invention overcomes the above difficulties and provides a simple, practical and comparatively inexpensive method by which such bolts may be manufactured.

20 In the drawings—

Figure 1 is a plan of the blank from which the staybolt is formed.

Figure 2 is an end elevation thereof.

Figure 3 is a sectional view through the 25 blank after the bore has been formed.

Figure 4 is an end elevation thereof.

Figure 5 is a sectional view through the blank after it has been reduced.

Figure 6 is an end elevation thereof.

30 Figure 7 is a sectional view through the blank after it has been upset to form the head.

Figure 8 is an end elevation thereof.

Figure 9 is a sectional view through the 35 blank after the bore has been reamed out to true up its cross section.

Figure 10 is a sectional view through the finished bolt after the threading operation.

In carrying out the present invention, we first provide a solid cylindrical blank 2 of materially greater diameter and lesser length than the finished bolt, as indicated in Figure 1. The blank 2 is then drilled or bored along its longitudinal axis to provide the hollow center or bore 3, as shown in Figures 3 and 4, which terminates materially short of the one end of the blank leaving a solid end 4 to provide stock from which the head of the bolt may be formed. The bore 3, which is formed in the blank, is materially shorter and of materially greater diameter than the bore of the finished bolt. Therefore, it may

be formed by a drill of materially greater diameter. Due to the greater diameter of the drill, compared with that which would 55 be usable to drill the finished bore, the drill has greater strength and may be forced at greater speed into the blank, and this coupled with the relatively shorter length of the bore reduces materially the time and cost 60 of forming the bores.

After the bore 3 is formed in the blank, the blank is heated and subjected to a rolling or other suitable reducing operation to simultaneously elongate and reduce the diameter 65 of both the blank and the bore over their entire length and form an elongated blank 4 and bore 5 having substantially the diameter of the finished bolt shank and bore as shown in Figures 5 and 6.

70 The elongated blank 4 is then reheated if necessary, and subjected to an upsetting operation to form the round head 6 and to slightly enlarge the shank portion 7 of the blank adjacent the head to form a tapered 75 area 8, as shown in Figures 7, 9 and 10.

The upsetting operation will cause the metal to flow inwardly adjacent the head end of the bore 5 forming a restriction 9. The bore 5 is then preferably reamed out by 80 passing a drill or reamer of the proper size therethrough, to remove the restriction 9 and true up the bore 5. This operation may be performed with considerable speed due to the fact that the bore is preformed and the 85 only substantial distortion will be the restriction 9.

If found desirable or necessary the outer 90 surface of the blank may be machined either before or immediately after the reaming operation.

The headed and reamed blank is then threaded adjacent its unheaded end, as at 10, to form a finished bolt consisting of the head 6, shank 7 having threads 10 at its unheaded 95 end, and the bore 5, as shown in Figure 10.

By forming staybolts in accordance with this invention, time is saved in the operation and a more accurately formed bolt is produced.

100 While we have described a certain specific sequence of steps for carrying out our method, it will be understood that we do not wish to be limited thereto, since various

modifications may be practiced without departing from the scope of our invention as defined in the appended claim.

We claim:

- 5 The method of making hollow staybolts, which includes providing a cylindrical blank of greater diameter and less length than the finished bolt, boring out the center of said blank for part of its length to form a bore of materially greater diameter than the bore in the finished bolt, reducing said blank over its entire length without providing an internal support for said bored out portion so as to simultaneously elongate and reduce 15 the diameter of said blank and said hollow center, upsetting the solid end of said blank to form a head portion extending beyond the closed end of said bore, permitting the metal of said blank to flow both outwardly and 20 inwardly over a short length of the bored out

portion of said blank adjoining the solid end during said upsetting operation to form a tapered portion of shank adjoining said head and to prevent the closing of the bore of said shank, said upsetting operation resulting in reducing the diameter of but not closing the bore in said blank adjacent its closed end and in shortening said blank to the length of the finished bolt, reaming out 25 said bore adjacent said head end of said blank to true up its diameter, and finally threading the unheaded end of said blank to finish the bolt.

In testimony whereof, I have hereunto set my hand.

HENRY M. CURRY, Jr.

In testimony whereof, I have hereunto set my hand.

LEO FINEGAN.
